(57) CLAIM

The ornamental design for a pastry cutter, as shown and
described.

DESCRIPTION

FIG. 1 is a front end, left side and top perspective view of
a pastry cutter showing my new design, in which the parts
shown in broken lines are environmental features only and
do not form part of the design claimed;

FIG. 2 is a rear end, right side and top perspective view
thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front end elevational view thereof; and,

FIG. 8 is a rear end elevational view thereof.
